UNITED STATES PATENT OFFICE

2,524,742

FABRICATED TOY BOAT CONSTRUCTION

Joseph K. Weddell, Longmeadow, Mass., assignor
to Milton Bradley Company, Springfield, Mass.,
a corporation of Massachusetts

Application August 16, 1948, Serial No. 44,433

1 Claim. (Cl. 46—93)

1

This invention relates to toy boat construction. The principal objects of the invention are directed to the provision of toy boat construction which is economical to produce and by reason of the novel features thereof the boat may have an appearance closely resembling a full size boat.

With the foregoing and various other novel features and advantages and other objects of my invention as will become more apparent as the description proceeds, the invention consists in certain novel features of construction and in the combination and arrangement of parts as will be hereinafter more particularly pointed out in the claim hereunto annexed and more fully described and referred to in connection with the accompanying drawings wherein:

Figs. 1 and 2 are plan and side elevational views of a boat construction embodying the novel features of the invention;

Fig. 3 is a perspective view of one end of the superstructure of the boat shown in Figs. 1 and 2;

Fig. 4 is a longitudinal sectional view through the hull of the boat shown in Figs. 1 and 2; and

Fig. 5 is a cross sectional view on the line 5—5 of Fig. 2.

Referring now to the drawings more in detail, the invention will be fully described.

The boat construction 2 of the invention includes in a general way a hull 4 and a superstructure 6.

The hull and superstructure may be any size or form and may be made from various materials in order to provide a boat having the desired characteristics.

Wood, of course, is ideally suited for boat construction but it is difficult, if not impossible, to produce toy boats from wood which have the appearance of or which may closely simulate ships.

This is accomplished according to this invention by making the hull from wood and the superstructure from molded plastic. In this way the superstructure may be made to simulate a ship and is readily accomplished in an economical manner.

As stated, the hull and superstructure may take various forms arranged to cooperate to provide the desired appearance.

The hull is hollowed out or recessed as at 8 and at the forward end is provided a horizontally extending slot 10 extending from the recess 8 to a vertical bore 12.

At the rear or stern end the hull is provided with a groove 14 extending horizontally rearwardly from the recess 8.

2

The stern portion of the superstructure is provided with a tongue 16 which is receivable in the slot 14 and the forepart of the superstructure is provided with a lug 18 which is receivable in the groove 10 and bore 12.

The tongue 16 is inserted in the slot 14 and the lug 18 is inserted in the groove 10 and bore 12 so that the superstructure is disposed on the hull about as shown.

10 A plug 20 is provided which is inserted in the bore 12 on top of member 18 and is adapted to be secured in the bore as by a tight fit, adhesive or by some other suitable means.

In this way, the superstructure and hull are secured together in assembled relation.

In the form of the invention shown, side walls 22 of the superstructure rests on the upper side of the hull and there may be inner side walls such as 24.

20 As stated, the hull and superstructure may take various forms and by reason of the separate components the superstructure may be made to simulate the appearance of various ships. Not only is the superstructure light in weight when made from plastic material but such material may provide various and numerous color effects.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the appended claim are therefore intended to be embraced therein.

What it is desired to claim and secure by Letters Patent of the United States is:

40 A toy-boat construction comprising in combination, a hull and a superstructure, said hull being in the form of an elongated body having an elongated recess open along the upper side thereof, said hull provided with a socket at the rear end of said recess below the upper side of said hull extending rearwardly from said recess and opening thereto and having a slot open on its upper side and extending forwardly from said recess, said superstructure formed from plastic material having side walls resting on the upper side of said hull, a tongue at the rear end of said superstructure extending downwardly and rearwardly therefrom into said socket and a lug

45 extending forwardly therefrom downwardly into

said slot and disposed below the plane of the upper side of said hull, and a plug secured in said groove over said lug.

JOSEPH K. WEDDELL. 5
